HANDLE FOR JAR AND BOTTLE OPENER

Radoslav Kovacevic, 300 N. State St.,
Chicago, Ill. 60610

Original design application May 26, 1969, Ser. No. 17,363.
Divided and this application Feb. 18, 1970, Ser. No.
20,841

Term of patent 14 years

Int. Cl. D8—05

U.S. Cl. D8—40

FIG. 1

FIG. 2

FIG. 3

FIG. 4

FIG. 5

FIG. 6

FIG. 1 is a top plan view of a handle for jar and bottle opener showing my new design;

FIG. 2 is a bottom plan view, with a typical opener shown in broken lines for environmental illustration only;

FIG. 3 is a front elevational view;

FIG. 4 is a rear elevational view;

FIG. 5 is a left end elevational view; and

FIG. 6 is a right end elevational view of FIG. 2.

This application is a division of application Ser. No. D. 17,363 of May 26, 1969.

I claim:

The ornamental design for a handle for jar and bottle opener, substantially as shown and described.
